UNITED STATES PATENT OFFICE

RICHARD E. SCHLETTNER, OF PHILADELPHIA, PENNSYLVANIA, ASSIGNOR, BY MESNE ASSIGNMENTS, TO TEXTILE MACHINE WORKS, OF WYOMISSING, PENNSYLVANIA, A CORPORATION OF PENNSYLVANIA

ATTACHMENT FOR FLAT-KNITTING MACHINES

Application filed July 25, 1928. Serial No. 295,285.

My said invention relates to an attachment for flat knitting machines, the present application being in part a continuation of my application Serial No. 66,916, filed November 5, 1925, now Patent 1,713,628, May 21, 1929. It is an object of the invention to provide special stops for yarn-guide carrier rods that have a variable traverse, such as are used for making clocks, for split-seam work, etc. The structure herein shown has several advantages over that described in said patent the first of which is that in the present instance I require but one chain to operate both the ratchet mechanism and the reversing means therefor. Second, but one friction box is required in the present instance regardless of the number of auxiliary yarn carrier rods employed, while in the disclosure of the patent a separate friction box was required for each yarn carrier rod. These friction boxes utilize considerable power when in operation and the elimination of several of them aids materially in speeding up production, produces better work, necessitates less repairs to the machine, and the machine is easier to operate. Third, the parts are more positive in their action by means of the attachment about to be described.

Referring to the drawings, which are made a part of this application and in which similar reference characters indicate similar parts:

Fig. 1 is a front elevation of so much of the machine as is necessary to a showing of the invention,

Fig. 2, a rear elevation of the same,

Fig. 3, a vertical section on line 3—3 of Fig. 1,

Fig. 4 a detail of parts shown in Fig. 3, on an enlarged scale,

Fig. 5, a plan showing my attachment,

Fig. 6, a plan partly in section, of means to prevent a certain operation when the narrowing means is in operation, and

Fig. 7 is a fragmentary elevation, partly in section, showing parts seen in Fig. 6.

In the drawings the reference numeral 1^a indicates the main frame of a flat knitting machine, 2^a, the front beam; 3^a, the back

beam; 4^a, the center bed; and 5^a, the main cam shaft. The numeral 80 designates the yarn carriers, mounted upon the usual longitudinally movable carrier rods 6^a, which latter are moved by the usual mechanism well known in this art. In Fig. 3 I have shown the second and third carrier rods, counting from the right, as operating splicing yarn guides with a variable stroke. Any one of the other rods may operate the guide for the body yarn with which the reinforcing yarns are interknitted, the travel of said rod being limited in any conventional or preferred manner, as by stops at the ends of the machine. In this disclosure of my invention, as in the foregoing showing, the novelty lies in the control of special stops for the several rods 6^a, limiting their path of travel, and thereby controlling the design. The nuts 9^a, 9^b in this case are the true rod-stops, and have the same function in this disclosure as in the showing in the application above referred to; i. e., determining the length of stroke of rods 6^a, and therewith the yarn carriers.

A right and left hand screw threaded spindle 11^a is journaled in bearings 12^a and carries thereon the nuts 9^a which in turn carry a supporting shaft 81 for the finger 82. Conventional abutment screws 7^a, 7^b are so located on the carrier rods that they can be made to engage the finger 82 at each side, whereby the finger and the shaft 81 will move with the carrier rod until stopped by a nut 9^a, the shaft being slidably mounted in nuts 9^a, 9^b, to permit endwise reciprocation of said shaft.

Fig. 5 shows two of the abutment screws backed off into idle position away from finger 82. Fig. 4, similarly shows a screw in full lines and another screw in dotted lines on the adjacent rod back of the finger 82. Fig. 1, shows two abutment screws on the same rod in operative position for engagement with the finger. Similar abutment screws on one or more other splicing yarn carrier rods enable me to secure them also to finger 82 for reciprocation with shaft 81 to the extent permitted by nuts 9^a, 9^b. The screw 11^a has an end extension 20^a fixedly

carrying oppositely toothed ratchet wheels 21^a and 22^a, and loosely strung arms 23^a and 24^a carrying spring controlled pawls 25^a and 26^a adapted to engage the respective ratchet wheels 21^a and 22^a, a notched rim and locking pin being employed as usual to prevent the accidental turning of the shaft 11^a. A pattern control chain 50^a hereinafter fully described, determines the selective engagement of the pawls, and the actuation of the connecting links 27^a and 28^a which are respectively connected to the loose arms 23^a and 24^a at their upper ends and to the levers 29^b and 29^c at their lower ends. These levers are pivoted at their forward ends to the main frame 1^a of the machine, and carry the rollers 30^a and 31^a, said rollers having a limited longitudinal movement on their respective lever carrier studs 32^a and 33^a and being adapted to ride upon special cams on the cam shaft 5^a, said cams having idle paths 34^b and 35^b and active paths 34^c and 35^c for the respective rollers all as in the form first described. Arms 40^a and 41^a are forked at one end and engage the rollers 30^a and 31^a respectively, and their opposite ends are attached to a horizontal shaft 42^a which extends practically the entire length of the machine. When motion is applied to the shaft 42^a by spring 43^a (Fig. 1) the arms 40^a and 41^a are caused to move and therewith the rollers 30^a and 31^a upon their respective lever carrier studs 32^a and 33^a from the idle paths of the cams on shaft 5^a to their operative paths 34^c and 35^c. A cam 45^a mounted on cam shaft 5^a, acting through the medium of a bell crank 44^a, returns the rod 42^a to the position shown in Fig. 1.

To automatically control the movement of this shaft 42^a, I employ the pattern chain 50^a, to which a step-by-step motion is imparted from cam shaft 5^a, through cam 51^a, and link connected lever 52^a, the latter having a pawl 53^a acting on the ratchet teeth of chain supporting wheel 54^a. Studs 55^a on the chain 50^a are adapted to act upon the lever 56^a carrying a shaft latch-member 57^a to raise and lower the latch. This latch 57^a slidably bears against a fixed shaft supporting bracket 58^a, and when in its lower position engages with its widest part between said bracket and a collar 59^a fixed on the shaft 42^a to temporarily hold the arms 40^a and 41^a in such position as to cause the rollers 30^a and 31^a to ride upon the idle portion of their respective cams, and when in its raised position the narrow lower end of the latch allows the shaft to move to the left to permit the said rollers to ride upon the active paths of the cams.

The raising of the lever 56^a and therewith the latch member 57^a is caused by the studs 55^a passing beneath the said lever. These studs are adjustable upon the pattern chain 50^a and the number of them controls the num-

ber of partial rotations of the screw shaft 11^a in one direction, while the distance between them controls the time between spindle movements and hence the distance between changes in the width of the ornamentation. 70

In order to impart movement to the screw shaft 11^a in a reverse direction, I employ a second set of studs 55^b mounted on the pattern chain 50^a and controlling a latch 57^b hung from a lever 56^b. This latch 57^b is like 75 latch 57^a and acts upon a shaft 42^b in like manner to the action of latch 57^a on shaft 42^a. Motion is imparted to the shaft 42^b by the small bell crank movement 44^b which imparts motion to the shaft 42^a, the shaft 42^b abutting against a bracket on shaft 42^a (Fig. 1) for this purpose. A shaft 83 (Figs. 1 and 3) extends across the machine from front to rear and carries on one end thereof an arm 84 having a forked end 85 straddling a pin 86 fixed to the shaft 42^b (see Fig. 1). A spring 43^b tends to move shaft 42^b to the left, holding it against latch 57^b or bracket 42' on shaft 42^b. Studs 55^a and 55^b can be mounted side by side so as to cause both of the preceding 80 mechanisms to operate in unison or studs 55^b may be mounted so as to cause lever 56^b and therewith arm 57^b to operate independently, in which case a partial rotation of the shaft 83 is caused through the 85 engagement of the forked arm 84 with the pin 86 on shaft 42^b. The opposite end of this shaft 83 carries a cross arm connection 87 (see Fig. 2) the outer ends of which are connected to the rods 88 and 89 and the upper 90 ends of which are connected to pawl lifters 90 and 91 respectively. These pawl lifters engage slidably with studs fixedly mounted in the pawls 25^a and 26^a, and when in one 95 position permit the engagement of the pawl 25^a with the ratchet 21^a at the same time holding out of action the pawl 26^a by preventing its engagement with the ratchet 22^a, and when in the reverse position permit the engagement of the pawl 26^a with the ratchet 22^a, and at the same time hold out of action the pawl 25^a from engagement with the ratchet 21. 100

The ratchet 21 is toothed so as to be engaged by the pawl 25^a which is hooked and operates upon its down stroke turning the screw shaft 11^a in a clockwise direction and moving the nuts 9^a toward each other, while the ratchet 22^a is toothed so as to be engaged by the pawl 26^a, which operates upon its up 115 stroke, moving the shaft 11^a in a counter clockwise direction and therewith the nuts 9^a away from each other. 120

Carried upon the supporting shaft 81, which is supported in the nuts 9^a, 9^a, is the stop finger 82 which is brought manually into the path of the stops 7^a, 7^a (see Fig. 4) when it is desired to limit the movement of the thread carriers by the means described. 125

During the narrowing operation (i. e., the 13^a

shaping of the leg portion of the stocking) it is essential that the mechanism controlling the design be held out of action, and in order to accomplish this, I employ a stop device 5 similar to that shown at 57^a Fig. 1 and operating upon the same shaft 42^a.

Mounted on a stud 98 adjacent the main cam shaft 5^a is the usual lever cam 99 which controls the narrowing mechanism, and attached thereto is an arm 92 (Figs. 6 and 7) which when the lever cam goes into action moves in the direction of the arrow (Fig. 6) against the collar 93 moving therewith the shaft 94 and the block 95 attached to the end 15 thereof, into the path of travel of the collar 96 fixed to the shaft 42^a and prevents the shaft from being shifted to the left by spring 43^a. It will thus be seen that during the narrowing of the stocking the shaft 42^a which 20 controls the operation of the design mechanism is prevented from working. A spring 97 tends to draw rod 94 toward the rear of the machine and so to normally hold the block 95 out of the path of collar 96.

25 The purpose of preventing operation of the screw-actuating means during narrowing arises out of the fact that if such means should happen to operate during narrowing the sinkers would cut off the yarns at the 30 fabric and so cause press-offs and seconds.

It will be obvious to those skilled in the art that various modifications may be made in my device without departing from the spirit of the invention and therefore I do not 25 limit myself to what is shown in the drawings and described in the specification but only as indicated in the appended claims.

Having thus fully described my said invention, what I claim as new and desire to 40 secure by Letters Patent, is:

1. In a straight knitting machine, reciprocating yarn guide carrier rods, a finger supported independently of said yarn guide carrier rods said finger being adapted to be connected to one or more yarn guide carrier rods to reciprocate therewith, and stops arranged to limit the movement of the finger in 45 opposite directions.

2. A device as in claim 1, combined with 50 means for moving the stops simultaneously toward or from each other.

3. A device as in claim 1, combined with 55 pattern-controlled means for moving the stops simultaneously toward or from each other.

4. A device as in claim 1, combined with 60 pattern-controlled means for moving the stops simultaneously toward or from each other, said pattern-controlled means controlling both the time and the direction of movement of the stops.

5. A device as in claim 1, combined with 65 pattern-controlled means for moving the stops simultaneously toward or from each other, and means for preventing operation

of said means during the narrowing operation.

6. In a straight knitting machine, reciprocating yarn guide carrier rods, a finger supported independently of the yarn guide carrier rods said finger being adapted to be connected to one or more yarn guide carrier rods to reciprocate therewith, stops arranged to limit the movement of the finger in opposite directions, and a reversely threaded spindle 70 connected to said stops for moving them toward or from each other.

7. A device as in claim 6, combined with 75 pattern-controlled means for rotating said spindle.

8. A device as in claim 6, combined with 80 pattern-controlled means for rotating said spindle, said pattern-controlled means controlling both the direction and the time of rotation of the spindle.

9. A device as in claim 6, combined with 85 pattern-controlled means for rotating said spindle, and means for preventing rotation of said spindle during the narrowing operation.

10. In a straight knitting machine, reciprocating yarn-carrier rods, a pair of stops, means for moving the stops toward or from each other, a reciprocatory shaft carried by 90 said stops and having its endwise movement limited by said stops, and means for connecting said shaft to one or more of said carrier rods.

11. A device as in claim 10, the stop-moving means being pattern-controlled to determine the direction and the time of such movement.

12. A device as in claim 10, the stop-moving means being pattern-controlled to determine the direction and the time of such movement, and means to prevent movement of the stops during the narrowing operation.

13. A device as in claim 10, the stop-moving means being pattern-controlled to determine the direction and the time of such movement, and means to prevent movement of the stops during the narrowing operation said last-named means being pattern-controlled.

14. In a straight knitting machine, reciprocating yarn guide carrier rods, a pair of stops, a reversely threaded spindle connected to 115 said rods for moving them simultaneously toward or from each other, a reciprocatory shaft carried by said stops and having its endwise movement limited by said stops, and means for connecting said shaft to one or more of said carrier rods.

15. In a straight knitting machine, reciprocating yarn guide carrier rods, a pair of stops, reversely threaded spindle connected to 125 said rods for moving them simultaneously toward or from each other, a reciprocatory shaft carried by said stops and having its endwise movement limited by said stops,

means for connecting said shaft to one or more of said carrier rods, means for rotating said spindle, and a single pattern chain controlling both the times and the direction of rotation of the spindle.

5 In testimony whereof I affix my signature.

RICHARD E. SCHLETTNER.
